UNITED STATES PATENT OFFICE.

NELSON LESLIE HYATT AND HARVEY LLOYD, OF DRESDEN, ONTARIO, CANADA.

AEROPLANE-PROPELLING DEVICE.

1,298,724.

Specification of Letters Patent. Patented Apr. 1, 1919.

Application filed December 10, 1917. Serial No. 206,526.

To all whom it may concern:

Be it known that we, NELSON L. HYATT and HARVEY LLOYD, citizens of Canada, and residents of Dresden, in the Province of 5 Ontario and Dominion of Canada, have invented certain new and useful Improvements in Aeroplane-Propelling Devices, of which the following is a specification.

This invention relates to aeroplane propelling devices and more particularly to a device for facilitating vertical ascension of an aeroplane.

The primary object of this invention is to provide a plurality of supplementary propellers arranged above the aeroplane and adapted to be operated by the aeroplane motor whereby the aeroplane may ascend vertically before the driving or traction propeller is brought into operation.

The invention also aims at the provision of a device that may be attached to an aeroplane for facilitating ascension of the aeroplane while the same is also moving forwardly, the construction being such as to permit simultaneous operation of the driving or traction propellers with the supplementary propellers which perform the work of elevating the aeroplane.

A further object of the invention is to provide a plurality of supplemental propellers for causing vertical ascension of the aeroplane and adapted to rotate in different directions whereby the equilibrium is maintained during ascension thereof.

Other objects of the invention will be apparent from a consideration of the following detailed description and a consideration of the accompanying drawings, wherein is illustrated the preferred form of our invention and in which:

Figure 1 is a front elevation of an aeroplane showing the invention applied thereto.

Fig. 2 is a top plan.

Fig. 3 is an enlarged sectional view of the attachment taken substantially on the line 15 3-3 of Fig. 2.

Fig. 4 is a fragmentary section taken on the line 4-4 of Fig. 2.

Fig. 5 is a fragmentary horizontal section taken substantially on the line 5-5 of Fig. 3.

The aeroplane includes the upper plane 1 and the lower plane 2 and the car 3 within which the motor is mounted. Attached to

the car 3 is a base flange 4 having a plurality of angularly disposed brace arms 5 radiating therefrom and provided with a central vertically extending standard in the form of a sleeve 6. A central power shaft 7 is arranged within the sleeve and extends 60 centrally through the base flange 4 and is provided at its lower end with a gear or sprocket 8 having a suitable connection with the motor whereby the shaft 7 may be driven when the motor is in operation. At the top 65 end of the standard 6 is a gear housing 9 and the upper end of the shaft 7 carries a beveled gear 10, while a plurality of beveled gears 11 are arranged within the housing and mesh with the gear 10 at diametrically opposite points. Connected to the gear housing 9 is a plurality of sleeves 12 radiating from the housing and embracing shafts 13 each of which projects into the gear housing 9 and carries one of the beveled gears 70 11 at its inner end. Since all of the gears 11 are in mesh with the beveled gear 10, all of the shafts 13 will rotate in the same direction when the shaft 7 is driven. At the outer end of the braces 5, we have provided bearings 14 which receive the outer ends of the sleeve 13 and have journaled therein the outer ends of the shaft 12, the latter being extended beyond the bearings 75 and provided with beveled gears 15. Gear casings 16 are arranged at the outer ends of the braces and inclose the gears 15 and the gears 17 carried by the propeller shafts 18 which are journaled in the upper portion of the gear casings 16. The ends of the propeller shafts 18 are extended above the gear casings and each carries a propeller 19.

Two of the propellers 19 disposed at diametrically opposite points are geared through the medium of the gears 15 and 17 95 so that they both rotate in the same direction as indicated by the arrows in Fig. 2 of the drawing. The other two propellers, however, are adapted to rotate in the opposite direction and therefore are geared, as 100 shown in Fig. 4 of the drawing. In this instance, the gear 15' mounted upon one of the shafts 13, is in mesh with the gears 17' at a point diametrically opposite from the point with which the gears 15 mesh 105 with the gears 17 for driving the propellers 19. This arrangement of the gears causes the propellers 20 to rotate in a direction

directly opposite from the direction of rotation of the propellers 19. Thus, the propellers 19 and the propellers 20, mutually coöperate to maintain the equilibrium of the aeroplane during ascension.

In order that the aeroplane will not tilt forwardly or rearwardly during ascension, we attach the base flange 4 at a point slightly rearwardly of the longitudinal center line of the planes 1 and 2, as shown to advantage in Fig. 2 of the drawing, and it will be obvious that this flange 4 may be attached to the car at a point that will cause the aeroplane to be held in a horizontal plane when the aeroplane is ascending, this point of connection being different with different types and makes of aeroplanes. The upper plane 2 has the brace arms 5 extended therethrough so that the propellers disposed above the upper plane and the length of these brace arms and the length of the central standard 6 may vary according to the distance that it is necessary for the propellers 19 and 20 to be disposed above the plane 1. The shaft 7 may be connected directly to the motor so that it will operate when the motor is operated to rotate the driving propeller B and a suitable clutch device may be provided to disconnect the shafts 7 from the motor when the aeroplane reaches the desired height. It will be understood, however, that it is not essential that the propeller B be still when the ascending propellers are rotating, as it will be obvious that the aeroplane may be moving forwardly while it is also ascending. The ascension, however, with the use of these propellers, will be greatly facilitated and the long starting runs now necessary before ascending will be unnecessary.

From the foregoing, it will be observed that a very simple and durable aeroplane elevating device has been provided, the details of which embody the preferred form. We desire to be understood, however, that slight changes may be made in the details of construction without departing from the

spirit of the invention or the scope of the claims hereunto appended:

We claim:

1. The combination with an aeroplane embodying a fuselage, a motor, and aerofoils, of a standard supported on the fuselage and extending upwardly therefrom, a plurality of shafts radiating from said standard above the uppermost aerofoil, a helicopter propeller arranged near the outer end of each shaft, means for rotating said propellers from said motor, said means arranged to rotate the diametrically opposed pairs of propellers in the same direction and the propellers of the pairs upon each side of the longitudinal axis of the aeroplane in opposite directions to maintain lateral stability of the aeroplane and impart an ascensional effort thereto.

2. The combination with an aeroplane embodying a fuselage, a motor and aerofoils, of a base flange attached to the upper surface of the fuselage, a tubular standard supported by said base flange, a gear housing mounted upon the upper end of said tubular standards, a plurality of shafts radiating from said gear housing, a plurality of angularly disposed braces formed upon said base flange and having bearings at their outer upper ends for the outer ends of said radiating shaft, said shaft being positioned above the uppermost aerofoil, a helicopter propeller arranged near the outer end of each shaft and supported by said angular braces, means for rotating said propellers from said shaft, means for rotating said shaft from said motor, said propeller rotating means arranged to rotate the diametrically opposed pairs of propellers in the same direction, and the propellers of the pairs upon each side of the longitudinal axis of the aeroplane in opposite direction to maintain lateral stability of the aeroplane and impart an ascensional effort thereto.

NELSON LESLIE HYATT.
HARVEY LLOYD.
